UNITED STATES PATENT OFFICE.

WALDO SHELDON, OF GREENWICH, CONNECTICUT.

WELL DRILLING.

Application filed May 9, 1924. Serial No. 711,981.

This invention relates to rotary well drilling apparatus and the objects of the invention are to provide power feed mechanism for the drill stem combined with the rotary table in such a way as not to interfere with the usual and ordinary operations of the rotary and arranged to apply any desired lifting or lowering force to the drill stem and at the same time to exert a guiding and controlling effect to overcome gyratory tendencies.

Various other objects and the novel features of construction, combination and relation of parts which make possible the attainment of the same will appear in the course of the following specification.

In the drawings accompanying and forming part of this specification, the invention is illustrated in one simple practical form, Figure 1 being a part sectional vertical elevation of the apparatus, Figure 2 a top plan view of the same and Figure 3 a bottom plan view.

The rotary table is indicated at 5 and is shown as of special construction in that it has an elongated dependent tubular extension or barrel 6, having a bearing in an elongated sleeve 7 forming a part of the base of the table. The long bearing thus provided steadies the table and keeps it running true under conditions of heavy strain.

Carried by the table and rotating therewith is a sleeve 8 keyed to turn with the table, in the illustration, by long keys 9 seated in keyways in the bore of the table and slidably received in keyways 10 in the sides of the sleeve 8, the latter being thereby forced to rotate with the table, but free to slide vertically therethrough.

The sleeve 8 is equipped at its upper end with appropriate drill stem engaging means the same being herein shown as slips 11 seated in a bushing or adapter 12 secured to the upper end of the sleeve.

The power for shifting the so-called chuck sleeve is supplied in the present disclosure by two hydraulic or pressure cylinders 13 supported on the base plate 14 at opposite sides of the table and having pistons 15 operating therein provided with rods 16 engaged at their lower projecting ends with the ends of a yoke 17 encircling the lower end of the

chuck sleeve at 18 with thrust bearings 19, 20 above and below the same for transmission of the lifting or lowering force to the annular thrust shoulders 21, 22 on the chuck sleeve.

To overcome the twisting effort on the power applying yoke, said yoke is shown as provided toward its outer ends with bearings 23 sliding over guide rods 24 secured to brackets 25 dependent from the I-beams 26 forming the supporting frame for the entire structure.

The water or other actuating fluid is admitted to and discharged from the power cylinders at opposite sides of the pistons therein by connections such as indicated at 27 under control of suitable valve mechanism and this mechanism is preferably of such a type as to control to an exact degree, the lifting or lowering force applied to the drill stem through the medium of the sliding and rotating chuck sleeve. This makes it possible to control the drilling operations to suit varying conditions which may be encountered. The yoke is positively guided independently of the piston rods so that the piston and piston rods are relieved of strain and operate freely under the applied pressure. The yoke and cylinders being suspended from the bed plate and located below the table are out of the way for the use of tongs or other devices employed in rotary drilling operations and when the chuck sleeve is fully lowered, the device may then be used as a straight rotary by simply employing adapters or bushings to fit the grief stem or drill pipe.

The lowering of the center of gravity effected by placing the yoke and cylinders below the table gives stability and steadiness of operation. In the construction illustrated, greater stability is afforded and constant alinement of the parts is insured by connecting and bracing the tubular bearing of the table, the guide rods and the cylinders by a two-part clamp 28 shaped to fit about these elements and having its parts connected together by bolts 29 extended through opposed lugs 30 on the respective parts. This clamp thus forms a tie between all the dependent portions of the apparatus, holding them together rigidly in permanently alined relation.

What is claimed is:

1. In well drilling apparatus, the combination of a base plate and an elongated bearing sleeve dependent from said base plate, a rotary table having a dependent elongated sleeve journaled in said elongated bearing sleeve and having bearing engagements therein at widely separated points at the upper and lower ends thereof, means below the base plate for bracing the lower end of said elongated bearing sleeve to enable the same to keep the rotary table running true under conditions of heavy strain, a sleeve slidably keyed within the elongated sleeve of the table and guided in its vertical movements by said elongated table sleeve and drill stem engaging means carried by the upper end of the sleeve which is thus slidably held in the table sleeve.

2. In well drilling apparatus, the combination of a base plate and an elongated bearing sleeve dependent from said base plate, a rotary table having a dependent elongated sleeve journaled in said elongated bearing sleeve and having bearing engagements therein at widely separated points at the upper and lower ends thereof, means below the base plate for bracing the lower end of said elongated bearing sleeve to enable the same to keep the rotary table running true under conditions of heavy strain, a sleeve slidably keyed within the elongated sleeve of the table and guided in its vertical movements by said elongated table sleeve, drill stem engaging means carried by the upper end of the sleeve which is thus slidably held in the table sleeve.

3. In well drilling apparatus, the combination of a base plate and an elongated bearing sleeve dependent from said base plate, a rotary table having a dependent elongated sleeve journaled in said elongated bearing sleeve and having bearing engagements therein at widely separated points at the upper and lower ends thereof, means below the base plate for bracing the lower end of said elongated bearing sleeve to enable the same to keep the rotary table running true under conditions of heavy strain, a sleeve slidably keyed within the elongated sleeve of the table and guided in its vertical movements by said elongated table sleeve, drill stem engaging means carried by the upper end of the sleeve which is thus slidably held in the table sleeve and power mechanism below the rotary table for positively raising and lowering the sliding drill stem driving sleeve, said sleeve having a downward movement sufficient to bring the upper end of the same down to the top of the table to leave the table clear for rotary drilling operations.

4. In well drilling apparatus, the combination of a base plate and an elongated bearing sleeve dependent from said base plate, a rotary table having a dependent elongated sleeve journaled in said elongated bearing sleeve, and having bearing engagements therein at widely separated points at the upper and lower ends thereof, means below the base plate for bracing the lower end of said elongated bearing sleeve to enable the same to keep the rotary table running true under conditions of heavy strain, a sleeve slidably keyed within the elongated sleeve of the table and guided in its vertical movements by said elongated table sleeve and drill stem engaging means carried by the upper end of the sleeve which is thus slidably held in the table sleeve and comprising a bushing seated in the upper end of the sliding sleeve and pipe gripping means seated in said bushing.

5. In well drilling apparatus, the combination of a base plate and an elongated bearing sleeve dependent from said base plate, a rotary table having a dependent elongated sleeve journaled in said elongated bearing sleeve, means below the base plate for bracing the lower end of said elongated bearing sleeve to enable the same to keep the rotary table running true under conditions of heavy strain, a sleeve slidably keyed within the elongated sleeve of the table and guided in its vertical movements by said elongated table sleeve, power cylinders dependent from the base plate at the sides of the table, pistons operating in said cylinders having downwardly projecting piston rods and a yoke carried by said piston rods having a relatively rotatable engagement with the lower end of the sliding drill stem driving sleeve.

6. In well drilling apparatus, the combination of a base plate and an elongated bearing sleeve dependent from said base plate, a rotary table having a dependent elongated sleeve journaled in said elongated bearing sleeve, means below the base plate for bracing the lower end of said elongated bearing sleeve to enable the same to keep the rotary table running true under conditions of heavy strain, a sleeve slidably keyed within the elongated sleeve of the table and guided in its vertical movements by said elongated table sleeve, power cylinders dependent from the base plate at the sides of the table, pistons operating in said cylinders having downwardly projecting piston rods, a yoke carried by said piston rods having a relatively rotatable engagement with the lower end of the sliding drill stem driving sleeve and guides for said yoke interposed between the cylinders and the dependent bearing sleeve.

7. In well drilling apparatus, a base having an elongated bearing sleeve, a rotary table having an elongated dependent sleeve journaled in said bearing sleeve, a sleeve slidably keyed in the table sleeve, drill stem engaging means carried by the upper end of said sliding sleeve and power mechanism below the rotary table having a relatively rotatable pressure applying connection with the lower end of said drill stem driving sleeve entirely below the rotary table.

8. In well drilling apparatus, a rotary table, means for rotating the drill stem carried by the table, power cylinders supported at opposite sides of the table and having pistons with downwardly projecting piston rods, a yoke connected with said piston rods for applying lifting or lowering force to the drill stem rotated by the table, a base for the

- rotary table having a lower bearing adjacent to the lower ends of the cylinders, downwardly projecting guides for the yoke and a brace engaged with the lower table bearing, the guides, and the cylinders, for maintaining all in proper relation.
8. In well drilling apparatus, supporting beams, a bed plate on said beams, a rotary table having an extended sleeve, a base for said rotary including an elongated bearing dependent from the bed plate and receiving the extended sleeve of the table, cylinders dependent from the bed plate and having downwardly operating piston rods, a yoke connected with the lower ends of said piston rods and a drill stem driving sleeve slidably keyed in the sleeve of the table and having a relatively rotatable engagement at its lower end with the yoke.
- 10 9. In well drilling apparatus, a rotary provided with an extended sleeve, a base for the rotary having a bearing for the lower end of said sleeve, a tubular member slidably keyed in said sleeve and provided 15 with drill stem engaging means, a non-rotating yoke having relatively rotatable connection with said tubular member, guides for said non-rotating yoke and power cylinders having piston rods connected with 20 said yoke.
10. In well drilling apparatus, supporting beams, a bed plate on said beams, a rotary having an extended sleeve, a base for said rotary mounted on the bed plate and including an elongated bearing for the sleeve dependent from the bed plate, guides dependent from the beams at opposite sides of said bearing, a yoke slidably engaged on said guides, cylinders supported in dependent relation from the bed plate and having piston rods engaged with the yoke, a sleeve slidably keyed in the sleeve of the rotary and having relatively rotatable connection with the sliding yoke at its lower end and drill 40 stem driving means carried by the upper end of said slidably keyed sleeve.
11. In well drilling apparatus, supporting beams, a bed plate on said beams, a rotary having an extended sleeve, a base for said rotary mounted on the bed plate and including an elongated bearing for the sleeve dependent from the bed plate, guides dependent from the beams at opposite sides of said bearing, a yoke slidably engaged on said guides, cylinders supported in dependent relation from the bed plate and having piston rods engaged with the yoke, and a drill stem engaging tubular member slidably keyed in the sleeve of the table and having a relatively rotatable connection with the yoke.
12. In well drilling apparatus, supporting beams, a bed plate on said beams, a rotary having an extended sleeve, a base for said rotary mounted on the bed plate and includ- 5 guides, and the cylinders, for maintaining all in proper relation.
- ing an elongated bearing for the sleeve dependent from the bed plate, guides dependent from the beams at opposite sides of said bearing, a yoke slidably engaged on said guides, cylinders supported in dependent relation from the bed plate and having piston rods engaged with the yoke, a drill stem engaging tubular member slidably keyed in the sleeve of the table and having a relatively rotatable connection with the yoke and a brace connecting the lower ends of the cylinders and the guides.
13. In well drilling apparatus, a rotary table having an extended sleeve dependent therefrom, a base for said table having a dependent elongated rigid bearing sleeve receiving the extended sleeve dependent from the table, a sleeve slidably keyed in the extended sleeve of the table and lowerable down to the top of the table to leave the space above the table clear for the usual rotary drilling operations, drill stem driving means carried by the upper end of the sliding sleeve and accessible over the top of the table and power means below the table having a relatively rotatable power applying connection with said drill stem driving sleeve for raising and lowering the same without obstructing the table.
14. In well drilling apparatus, a rotary table having an unobstructed top clear for rotary drilling operations, power cylinders located at the sides of and below said table, downwardly acting pistons in said cylinders having downwardly projecting piston rods, a yoke connected with said piston rod and located entirely below the table and a drill stem driving sleeve having a freely rotatable connection with said yoke at its lower end, said sleeve being slidably keyed in the table so as to partake of the rotation of the same and provided at its upper end with drill stem gripping means freely accessible over the top of the table.
15. In well drilling apparatus, a rotary table, power cylinders located at opposite sides and extending below said table, a drill stem driving sleeve slidably keyed in said table and extending between the power cylinders, downwardly projecting guides located between said cylinders and the drive sleeve, a yoke slidably engaged with said guides and having a relatively rotatable connection with the lower end of the drive sleeve and pistons in the cylinders connected with the yoke at the outer sides of said guides.
16. In well drilling apparatus, a base having an elongated large diameter bearing sleeve, a rotary table having an elongated dependent large diameter barrel extension journaled in said sleeve, power cylinders supported by the base at opposite sides of

said sleeve and below the top of the table, pistons operating in said power cylinders and having projecting piston rods, a non-rotating power applying yoke actuated by
5 said piston rods, a drill stem driving sleeve slidingly keyed in the dependent barrel of the table, thrust transmitting connections between the yoke and one end of the drive sleeve, a drive bushing secured in the upper end of the drive sleeve and drill pipe gripping means seated in said bushing.

In witness whereof, I have hereunto set my hand this 2nd day of May, 1924.

WALDO SHELDON.
